UNITED STATES PATENT OFFICE.

ERWIN C. VROMAN, OF WATERTOWN, NEW YORK, ASSIGNOR TO THE NEW YORK AIR BRAKE COMPANY, A CORPORATION OF NEW JERSEY.

SPEED-RESPONSIVE DEVICE.

Application filed April 18, 1925. Serial No. 24,240.

This invention relates to speed responsive electrical switches and particularly to a speed responsive multiple contact switch intended for use as a part of an automatic control mechanism on railway trains.

While many of the features of the invention are applicable to the general field in which speed responsive switches may be used, this invention involves certain features 10 which particularly adapt it for use in the train control field and for this reason a brief statement of the requirements in this field of use will be given.

Train control mechanisms have been devised 15 which produce applications of the brakes automatically if the engineer passes a caution signal or a danger signal set against him or if he exceeds a certain maximum speed. These systems are objectionable because it is occasionally necessary for a train to pass a caution signal and enter a block, and it is entirely safe to do so provided the train enters at a reasonable speed. Similarly it is occasionally necessary for a 20 train to pass a danger signal and enter the danger block, and it is entirely safe to do so provided the train enters the block at a reasonable speed.

Consequently, systems have been proposed 25 which include a speed responsive switching device associated with hold-out mechanisms so contrived that if the engineer manipulates the caution hold-out mechanism when passing a caution signal, he may prevent an automatic application of the brakes if, and only if, the speed is below a fixed value determined by the setting of the speed responsive switch. A similar arrangement is provided on the danger or stop circuit, so 30 that the engineer may pass a danger signal set against him if at the time of passing he manipulates a corresponding hold-out device and if at the time the train is proceeding at a low speed (much lower than that at which 35 he is permitted to pass a caution signal), this action also being controlled by a speed responsive switch. The two functions can conveniently be secured by the use of two separate sets of contacts associated with a 40 single speed responsive mechanism. A third contact may be added to apply the brakes directly if the train speed exceeds some chosen maximum, regardless of the indications of the signal mechanism.

55 The speed responsive device must be oper-

ative without manipulation for either direction of travel of the engine or car to which it is applied and it must respond with considerable precision if annoying interferences with train movements are to be 60 avoided. Furthermore, it is desirable to apply such a switch directly to the wheel or axle, and in such case the device is not spring borne and is necessarily subjected to severe shocks and to some exposure to the 65 weather. Unless it is so designed that the various contacts are relieved from wear as far as possible, accuracy cannot be maintained.

Many mechanisms have been proposed and used experimentally, most of them based on 70 a centrifugal governing principle. Such devices have not proved satisfactory, first, because the action of the governor is deranged by vibration, inclination of the vehicle, and similar causes; and second, because the 75 parts are subjected to very severe wear. Such wear is particularly pronounced in the case of brushes commonly used with rotating slip rings and commutators. So far as I am aware, no device has heretofore been 80 devised which meets in a practical and satisfactory manner the requirements of the service.

The invention makes use of the general 85 principles underlying the induction type, alternating current motor. There is a rotating field formed by a plurality of permanent magnets; there is an armature mounted for limited rotation between limit stops and carrying a short-circuited winding; and there is a spring mechanism which 90 tends to retain the armature in a neutral or mid-position. The rotation of the field magnets in either direction exerts a turning moment on the armature and swings it 95 in one or the other direction through a variable angle depending on the direction and rate of rotation of the field.

The armature carries a specially shaped 100 insulated contact on which bear three brushes, each controlling a corresponding one of the three circuits above alluded to, and a fourth brush connected to a common return for such three circuits. This contact is so shaped that the three circuits 105 are interrupted successively at proper speed intervals.

It has been found in devices of this sort 110 that while the torque exerted by the field on the armature as a result of speed varia-

tions varies quite decidedly in the lower ranges, the variation at the higher speed range is less. Consequently it is desirable to provide a secondary torque-transmitting means having a critical point at which such secondary means comes suddenly into action at the highest or limiting speed.

Hence the reaction between the field and the armature is used to actuate the caution and danger contacts, and a centrifugal friction device is provided which at the maximum speed produces frictional engagement between the field and the armature, and thus suddenly produces the additional torque necessary to move the speed limiting brush off the armature contact. In this way I combine the smoothly graduated characteristic of the electro-magnetic action throughout the normal speed ranges with sudden and pronounced responses at a maximum speed.

The preferred embodiment of the invention is illustrated in the accompanying drawings, in which:

25 Fig. 1 is a vertical axial section showing the complete device as it appears attached to a pony truck wheel;

30 Fig. 2 is a section on the line 2—2 of Fig. 1 with certain portions broken away;

35 Fig. 3 is an enlarged fragmentary section on the line 3—3 of Fig. 2, showing the construction of the frictional mechanism which acts to connect the field and the armature at the critical maximum speed.

40 Fig. 4 is a portion of the hub of a pony truck wheel is shown at 6 in dotted lines. To this is connected by means of machine screws 7 an adapter 8 whose form is dependent on the size and form of the truck wheel. The purpose in using the adapter is to permit the standardization of all other parts of the device according to principals well understood by those familiar with machine design. The adapter 8 receives directly the base plate 9 on which seats a cover 10, and the adapter base and cover are connected together by a series of machine screws 11. All these parts are constructed of brass.

45 Directly mounted on the base plate 9 by means of a plurality of machine screws 12 is a circular series of V-shaped permanent magnets 13. The arrangement of these magnets is clearly shown in Figs. 1 and 2, and they form a complete circle except that one magnet is omitted from the series to give space for the frictional device, clearly shown in Figs. 2 and 3. This consists of a guide member 14 held to the base 9 by means of a cap screw 15 and provided with a guide-way in which there slides, in a direction radial to the base 9, a plunger 16 having a head or brake shoe member 17 at its outer end. A machine screw 18 whose end engages in a slot or key 19 on the plunger 16 prevents rotation of the plunger 16 in the guide 14.

The plunger is urged radially inwards by means of a coil spring 20 which surrounds it and which seats against a washer 21 adjustable on the plunger 16 by means of a nut 22 and a check nut 23.

At the center of the base plate 9 there is a circular aperture and an adjacent seat for the outer race of an annular ball bearing indicated generally by the numeral 24. At the center of the cover 10 there is also an opening provided with a seat for the outer race of a similar annular ball bearing indicated generally by the numeral 25. This race is held in place by means of an annular plug 26. The inner races of the bearings 24 and 25 are fixed on a shaft 27. The inner race of the bearing 25 is mounted directly on this shaft, while the inner race of the bearing 24 is fast on a collar 28 which in turn is fast to the shaft.

There is a dust guard 29 between the collar 28 and the base 9. There is a dust guard 30 between the annular plug 26 and the shaft 27, and another, 31, between a collar 32 fast on the shaft 27 and the cover 10. A cap plate 33 mounted on the base 9 covers the end of shaft 27 and with the dust guard 29 encloses the ball bearing 33.

The base 9 and its connected parts rotate with the wheel 6, and shaft 27 is held at rest by means of an angle fitting 34 screwed on its outer end, the fitting 34 being connected by a nipple 35 with a short length of stiff rubber hose 36 whose upper end is connected to a part of the frame of the vehicle (not shown). The hose 36 and fitting 34 serve as a conduit for electrical wiring connections, hereinafter described, and the hose retains the shaft 27 against rotation and at the same time permits minor movements, incident to vibration and the like, which are unavoidable under practical operating conditions.

50 Mounted on the shaft 27 between the bearings 24 and 26 are two annular ball bearings 37 which carry a hub 38. Locked to the hub 38 by means of a threaded clamp ring 39 is a cup-shaped armature 40 of magnetic material whose rim surrounds the pole pieces of the magnets 13, there being a small air gap, approximately .015 inches. To one side of the magnets the armature 40 carries a single short-circuited winding in the form of a copper ring 41. This is held in place by a series of rivets 42 and is insulated from the armature 40 by means of a thin strip of insulation 43 underlying the windings and by bushings 44 completely surrounding the rivets.

55 Locked on the shaft 27 by means of a threaded sleeve 45 is a contact carrier plate 46. This is provided at its lower end with a stop lug 47 which coacts with two stop pins 48 on the armature 40. Near its upper end it carries four aligned contact fingers 49, 50, 51 and 52 all insulated from the plate

46 and all having their effective contact points in a straight line. These contacts 49 to 52, inclusive, bear against a contact plate 53 which is mounted in a bed of insulation 54 carried on the armature 40, so that except for the contacts 49 to 52, inclusive, the contact 53 is completely insulated.

When the vehicle is at rest, the armature stands so that the line connecting the contact points of the contacts 49 to 52, inclusive, coincides with the center line of the contact 53. The margins of the contact 53 are so shaped that the contacts 49, 50 and 51 pass clear of the contact 53 successively in the same sequence and for the same displacements of the armature 40, clockwise or counter-clockwise, from its normal zero position, shown in Fig. 2. The armature is constantly urged towards this position by a double spring structure mounted chiefly on the armature 40 and reacting with a portion of the plate 46 which, being carried by the shaft 27, is fixed in position.

There is a spring housing 55 which has threaded extensions 56 at its two ends. These pass through lugs 57 on the armature 40 and may be adjusted therein by means of opposed nuts 58. The housing 55 has within its ends spring seats to receive two opposed coil springs 59 whose inner ends bear on a thrust block 60 guided in a radial slot on the plate 46. Consequently, the armature 40 may rotate in either direction against resistance by one or the other of the springs 59 and the zero or neutral position of the armature may be fixed by adjusting the nuts 58. The movement of the armature in each direction is limited by a corresponding one of the two pins 48 which collide with the stop lug 47.

There are individual electrical connections 61, 62, 63 and 64 for the four contact fingers 49 to 52, inclusive, and these extend through a passage 65 formed in the shaft 27 to receive them. This passage leads to the end of the shaft so that the connections pass off through the angle fitting 34 and the hose 36. The contact 49 is the one which clears the contact 53 at the lowest speed. Hence in a stop mechanism such as described it would control the danger hold-out circuit. Contact 50 is the next to clear and therefore controls the caution hold-out circuit. Contact 51 is the last to clear and directly controls a train stop mechanism, usually one which applies the brakes. Contact 52 is merely the common return contact for the other three. After the contacts 49 and 50 have cleared the contact 53 and just as the critical speed is reached, the plunger 16 will have moved out under centrifugal force far enough to move the brake shoe 17 into contact with the inner face of the armature 40. The additional force thus imposed on the armature 65 ring shifts it far enough to clear the contact

51. At all low speeds the plunger 16 and its brake shoe are ineffective.

The operation of the device will be readily understood from the description already given. It will be observed that the mechanism is simple and rugged in construction; that those parts which are in constant motion are mounted on ball bearings; and that the brushes are subject only to such wear as is occasioned by motion of the armature incident to speed changes. The device responds in the same manner, regardless of the direction of rotation of the wheels, and its response may readily be adjusted by changing the form of the contact 53 and by changing the stiffness of the springs 59, either or both, as may be found convenient. The use of the centrifugal plunger 16 permits a sharp response of the device to the critical maximum speed, while permitting advantage to be taken of the flexibility and smooth action characteristic of the reaction between the armature and the field. This critical response is readily adjustable. Finally, the device is completely housed against the weather and is adaptable to existing equipment without substantial change therein.

Obviously various structural changes are possible and I do not limit myself to the specific structure except to the extent specified in the claims.

Important features of the invention are the arrangement of the device so that it is in perfect running balance and so that it operates in the same characteristic manner in both directions of rotation. To secure this result the simplest arrangement is to make the contact 53 symmetrical with respect to a line radial to the armature and to cause the contacts 49 to 52, inclusive, to contact along this radial axis of symmetry when the device is in its normal neutral or mid-position. The exact shape of the contact 53 is a function of the arrangement of the contacts 49 to 52, inclusive, of the speeds at which the various controls are to be effective, and of the motion characteristic of the armature 40 under varying speeds.

What is claimed is:

1. A speed responsive device comprising in combination a rotatable field member; a rotatable armature member associated therewith; means for rotating one of said members in either direction at variable speeds; yielding means arranged to permit limited rotary displacement of the other of said members conforming in direction and extent with the direction and speed of rotation of the first member; and a series of electric switch contacts arranged to be successively opened and closed in a chosen order by the displacement of said other member in either direction relatively to its normal position.

2. A speed responsive device comprising in combination a rotatable field structure; a

rotatable armature associated therewith; means for rotating said field structure in either direction at variable speeds, yielding means arranged to permit limited rotary displacement of the armature conforming in direction and extent with the direction and speed of rotation of the field structure; and a series of electric switch contacts arranged to be successively opened and closed in a chosen order by the displacement of said armature in either direction relatively to its normal position.

3. A speed responsive device comprising in combination a rotatable field structure; a rotatable armature associated therewith; means for rotating said field structure in either direction at variable speeds; yielding means arranged to permit limited rotary displacement of the armature conforming in direction and extent with the direction and speed of rotation of the field structure; a contact mounted on said armature, the contour of said contact being symmetrical with reference to a line radial to the armature; and a series of contacts bearing on said armature-carried contact in a line which, in the neutral position of the armature, coincides with said radial line.

4. A speed responsive device comprising in combination a rotatable field member; a rotatable armature member associated therewith; means for rotating one of said members at variable speeds; yielding means restraining the other of said members and arranged to permit rotary displacement thereof to an extent conforming to the speed of rotation of the first member; and a centrifugal brake device arranged to operate at a critical speed to connect said members frictionally.

5. A speed responsive device comprising in combination a rotatable field member; a rotatable armature member associated therewith; means for rotating said field member in either direction at variable speeds; yielding means arranged to permit limited rotary displacement of the armature member, conforming in direction and extent with the speed and direction of rotation of said field member; and a centrifugal brake device responsive to the speed of said field member

and arranged to establish a frictional connection between said members when said field member attains a chosen speed.

6. A speed responsive device comprising in combination a rotatable field member; a rotatable armature member associated therewith; means for rotating one of said members in either direction at variable speeds; yielding means arranged to permit limited rotary displacement of the other of said members conforming in direction and extent with the direction and speed of rotation of the first member; a centrifugal brake device arranged to come into action at a critical speed and establish a frictional connection between said members; and a series of electric switch contacts arranged to be successively opened and closed by the movements of said other member, the actuation of the last contact of the series being effected at said critical speed by said frictional device.

7. A speed responsive device comprising in combination a rotatable field structure; a rotatable armature associated therewith; means for rotating said field structure in either direction at variable speeds; yielding means arranged to permit limited rotary displacement of the armature conforming in direction and extent with the direction and speed of rotation of the field structure; a centrifugal brake device interposed between said field structure and armature and arranged to come into action at a critical speed to establish a frictional driving connection between said field structure and said armature; a contact member mounted on said armature and having a contour symmetrical with reference to a line radial to said armature; and a plurality of contact members engaging said contact member in a line which, in the neutral position of the armature, coincides with said radial line, the parts being so arranged that the brushes clear said contact successively as the armature is displaced from its neutral position and the last brush is about to clear said contact as the field approaches said critical speed.

In testimony whereof I have signed my name to this specification.

ERWIN C. VROMAN.
